(57) **CLAIM**

The ornamental design for an automotive wheel, as shown and described.

DESCRIPTION

FIG. 1 is a perspective view of an automotive wheel, showing my new design;

FIG. 2 is another perspective view thereof;

FIG. 3 is a front view thereof;

FIG. 4 is a perspective view of a second embodiment of an automotive wheel, showing my new design;

FIG. 5 is another perspective view of FIG. 4;

FIG. 6 is a front view of FIG. 4;

FIG. 7 is a perspective view of a third embodiment of an automotive wheel, showing my new design;

FIG. 8 is another perspective view of FIG. 7;

FIG. 9 is a front view of FIG. 7;

FIG. 10 is a perspective view of a fourth embodiment of an automotive wheel, showing my new design;

FIG. 11 is another perspective view of FIG. 10;

FIG. 12 is a front view of FIG. 10; and,

FIG. 13 is a side view of the automotive wheel in FIGS. 1-12.
